This technical drawing, labeled 'Fig. 7' at the top, is a cross-sectional view of a mechanical assembly. The assembly is housed within a rectangular frame with vertical supports. A central vertical rod, labeled 'a', passes through several components. A horizontal plate, labeled 'p', is positioned above a section labeled 'p2'. A vertical plate, labeled 'm', is located to the right of 'p2'. The lower section of the assembly is more complex, featuring a vertical rod labeled 'b' and various mechanical parts labeled with letters and numbers. A date, '4/19/26', is visible on a plate within this section. The drawing is filled with hatching and cross-hatching to distinguish different parts. A second figure, 'Fig. 8', is shown below the main drawing, indicating a related view or detail.

UNITED STATES PATENT OFFICE.

BERTRAM C. KENYON, OF MISHAWAKA, INDIANA.

GAME DEVICE.

No. 830,078.

Specification of Letters Patent.

Patented Sept. 4, 1906.

Application filed May 6, 1905. Serial No. 269,117.

To all whom it may concern.

Be it known that I, BERTRAM C. KENYON, a citizen of the United States, residing at Mishawaka, in the county of St. Joseph and State of Indiana, have invented a certain new and useful Improvement in Game Devices, of which the following is a specification.

My invention relates to game devices in which balls are automatically played; and in the particular form of invention here shown the devices are so constructed and arranged as to play the game of "pool," the cue being automatically shot, the balls being then collected and subsequently repositioned with the cue-ball in front of the cue and the object balls arranged in the form of a triangle near the opposite end of the table; as in the regular game.

The general object of the invention is to provide mechanism for automatically playing a game of this general character, while the more specific objects which render the general object possible of attainment are to provide, first, means for operating the cue; second, means for lowering the table to inclined position for delivering the scattered balls to the collecting means and subsequently raising the table to horizontal position for play; third, means for collecting and returning the balls to their receptacles after they have been played; fourth, means for raising and lowering the cups or platforms which constitute ball-receptacles for lifting the balls back to the table in position for play; fifth, means for adjusting the object balls within their receptacle, which object is obtained in the present instance by agitating said receptacle; sixth, an escapement and means for controlling the time of operation thereof; seventh, ball-controlled tally means and mechanism for operating the same; eighth, means whereby the above-mentioned mechanisms and devices are correlated so as to constitute a single automatically-operating game device.

I attain these objects by the mechanism illustrated in the accompanying drawings, in which—

Figure 1 is a general perspective view of the complete device. Fig. 2 is a plan view thereof. Fig. 3 is a view of the escapement looking in the direction of the arrows from the vertical plane indicated by the line 3 3, Fig. 6. Fig. 4 is a side elevation of the complete machine looking from the operating-lever side thereof with the side of the casing

removed to exhibit the working parts. Fig. 5 is a plan view of the device with the tabletop removed. Fig. 6 is a plan view taken on line 6 6, Fig. 4. Fig. 7 is a vertical sectional view taken on line 7 7, Fig. 6, and looking in the direction of the arrows on said line. Fig. 8 is a fragmentary sectional view of the master-shaft and parts mounted thereon. Fig. 9 is a side elevation showing the relationship of the drop-table, the cue, the ball-receptacles, and parts for operating and correlating the same. Fig. 10 is a fragmentary plan view showing the trough wherein the balls are retained prior to their release by the retaining-gate. Said figure also shows portions of the runways leading from said trough to the object-ball receptacle and the cue-ball receptacle. Fig. 11 is a side elevation of the compound lever which operates the ball-receptacles. Said figure also shows the lifting-lever for effecting the ultimate or final rise of the ball-receptacles. Fig. 12 is a side elevation of the drop-table and means for raising and lowering the same. Fig. 13 is a side elevation of the cue and of the means whereby it is operated. Fig. 14 is a side elevation of the shaking mechanism designed to agitate the object balls in the object-ball receptacle for adjusting the balls therein. Fig. 15 is a side elevation of the cam and other devices for releasing the rod whereby the ball-receptacles are locked in the "normal" or "rest" position, which position is intermediate of the highest and lowest positions. Fig. 16 is a side elevation of the above-mentioned rod and of the pivoted and cam-operated dog which temporarily sustains said rod and the lifting-yoke in highest position. Fig. 17 is a fragmentary elevation showing a portion of the above-mentioned rod and of the dog whereby it is locked in normal position. The parts here illustrated are operated by the parts shown in Fig. 15. Fig. 18 is a fragmentary detail view showing the preferred means for transmitting power to the master-shaft from the operating-handle. Fig. 19 is a fragmentary detail view of the hook for engaging the yoke or projection on the escapement-arresting rock-shaft to hold the arresting-finger away from the fan-wheel of the escapement. Fig. 20 is a sectional elevation on line 20 20, Fig. 5, showing the construction and arrangement of the tally means. Figs. 21, 22, and 23 are detail views, in side elevation, illustrating the operation of the parts whereby the tally-box is reciprocated.

Fig. 24 is a plan view of the tally-box. Fig. 25 is a sectional plan view thereof, taken on line 25 25, Fig. 26. Fig. 26 is a vertical sectional view taken on line 26 26, Fig. 25. Fig. 27 is a fragmentary view of a delivering-sector, showing a delivering-finger mounted thereon.

Similar letters refer to the similar parts throughout the several views.

10 The present embodiment of this invention consists of a miniature game of pool which is entirely automatic, in that it shoots the cue, so as to propel the cue-ball toward the object balls, then collects the scattered balls, and re-positions them in readiness for a repetition of the play. All that is required on the part of the operator is to swing the operating-handle from the position shown in Fig. 1 to a position about ninety degrees therefrom down-
ward to the right.

15 With the exception of the operating-handle *a* the working parts are inclosed within the cabinet or casing *b*, which is provided in the present instance with two interior horizontal plates *b'* and *b''*, which form supports for the greater portion of the interior mechanism. The table *c*, whereon the object balls *d* and cue-ball *d'* roll, is mounted near the top of the casing, and it is desirable that
20 a glass cover *b''* be mounted at a distance above the table slightly greater than the diameter of the said balls *d d'*.

25 In the present and preferred design of the machine all of the acting parts are operated or controlled from one or both of the two shafts *e* and *f*, which will be hereinafter referred to as the "master-shaft" and "motor-shaft," respectively. Said shafts are journaled in suitable stationary hangers *e'* and *f'*, respectively, which in the present instance are rigidly mounted on the plate *b'*, as best shown in Figs. 7 and 8, respectively.

30 The master-shaft *e* is rotated in a forward or clockwise direction when viewed as, for example, in Fig. 1 by means of the operating-handle *a*, which for the convenience of the operator is limited in its throw to an angle of about ninety degrees between the stoppins *b' b''*, fixed in casing *b*. It is desirable that handle *a* be operative upon shaft *e* while said handle is rotating from the normal or rest position (shown in Fig. 1) to the end of its throw, but be non-operative upon said shaft during the return movement, whereby
35 said handle may of itself return to normal position independently of said shaft. The preferred means for obtaining this effect is best shown in Figs. 6, 8, and 18, although I do not herein claim such construction, as it forms
40 the basis of a separate application for United States patent for coin-controlling mechanism filed by me on the 17th day of April, 1905, Serial No. 256,005. In the device here shown for rotating shaft *e* in the forward or clockwise direction handle *a* is bolted or

otherwise rigidly secured to the sleeve *a'*, which is loosely mounted on said shaft, so as to straddle the collar *e''*, pinned or otherwise rigidly secured to shaft *e*. Said collar has a shoulder *e''*, adapted to be engaged by the
70 nose of dog *a''*, pivotally mounted upon sleeve *a'*. Said dog is spring-influenced to remain out of engagement with said shoulder. A coin-chute *b''* is mounted in casing *b* in such manner as to lead a coin to engage the pin *a''* on said dog and throw the dog into engagement with shoulder *e''* when said handle and sleeve are rotating in the forward direction. I do not desire to be limited to this construction, however, as any means may be substituted by which the shaft *e* will be rotated in a forward direction when handle *a* is moving in a forward direction, but will permit said handle to return to normal position independently of said shaft.

75 Handle *a* is urged to return to normal position by means of a spring *a''*, which is secured at one extremity to plate *b''* and at the other extremity to the arm *a''*, rigidly secured to sleeve *a'*. The forward rotation of master-shaft *e* causes the forward rotation of motor-shaft *f*; but the return rotation of shaft *e* is caused by the return rotation of shaft *f*, which acts under the force of spring *g*. The construction is best shown in Figs. 4, 5, 6, and 95 7, wherein it is shown that the sheave *e''* is rigidly secured to shaft *e* in line with the sheave *f''*, which is rigidly secured to shaft *f*. A chain *e''* is fastened at one end to sheave *e''* and at the other end to sheave *f''*, and thereby serves to transmit motion from one to the other. The parts are preferably so proportioned that the shaft *f* will be rotated practically one complete revolution by rotating handle *a* only about ninety degrees. A sheave *f''* also rotates with shaft *f* and for convenience of manufacture is made integral with sheave *f''*, as shown in Fig. 7. A chain *g'* is fastened at one end to said sheave *f''* and at the other end to the tension-spring *g*, above mentioned. Said spring is fastened to the casing *b* or other stationary part, and the parts are so constructed that rotating handle *a* forward will stretch said spring; but when said handle is released the spring will pull chain *g'*, so as to rotate shaft *f* in the return direction, which in turn will rotate shaft *e* back to normal position.

100 It is during the return rotation of motor-shaft *f* that the active operations of most of the parts occur, and spring *g* may therefore be considered as the motive power for driving the parts. This taken in connection with the governing influence of the escapement causes the parts to operate at a uniform speed regardless of whether the handle is moved fast or slowly.

105 *Escapement.*—The construction of the parts constituting the escapement are best shown in Figs. 3, 6, and 7. The shaft *h* is
110

115

mounted in the stationary hangers b^6 , secured to plate b' , and has a fan h' rigidly fastened thereto, which serves to retard and govern the speed of rotation of said shaft by reason of the resistance of the air to said fan. Shaft h is connected to shaft f through a series of reduction-gears h^2 , which are also mounted in said hangers b^6 . It is evident that when motor-spring g is fully stretched 5 it will exert more force on shaft f than when said spring is more nearly collapsed and shaft f has nearly completed its return rotation. In order to offer greater resistance to the rotation of shaft f at the beginning of the 10 return movement thereof when the spring is strongest, it is desirable to provide an auxiliary fan h^3 , which is loosely and shiftably mounted on shaft h at the side of fan h' and has a clutch part h^4 , adapted to fit into the 15 clutch part h^5 on fan h' . A pivoted shifting-lever h^6 is arranged to control the lateral position of fan h^3 without preventing its rotation, and said lever is spring-influenced to tend to shift the said fan h^3 into connection with fan 20 h' . A cam f^1 , rigidly attached to shaft f , is also adapted to act on lever h^6 and is so timed as to permit fan h^3 to remain in contact with and be rotated by fan h' during the fore part of the return rotation of shaft f and to 25 throw said fan h^3 out of engagement with fan h' toward the end of said return rotation. Thus there will be a greater fan-surface rotating while the spring g is under greatest tension and less surface when the spring is 30 more nearly collapsed.

A ratchet-wheel f^5 is rigidly secured to shaft f and is adapted to drive the reduction-gears h^2 and fan h' always in the same direction by acting upon the pawl h^7 , mounted on 35 such one of the gear-wheels h^2 as is concentric with and loose upon shaft f . Thus the escapement permits shaft f to rotate in a forward direction without being affected; but said shaft upon its return rotation drives said 40 escapement and is governed thereby.

In order to prevent premature operation of the escapement, arresting mechanism is provided, which in the present case consists of a finger i , rigidly secured to the rock-shaft i' in such manner that the extremity of 45 said finger or arrester may be swung into and out of the path of fan h' . Said shaft i' is journaled in suitable fixed bearings—for example, the hangers b^6 —and is itself operated by the arm i^2 . (Best shown in Figs. 3 and 4.) Said arm i^2 is rigidly secured on shaft i' and is 50 spring-influenced to hold finger i in position to arrest fan h' . Said arm is operated by means of the arm a^6 , fastened to sleeve a' , so 55 as to rotate with handle a . The parts are so designed that arm a^6 will not engage arm i^2 to release the escapement until said handle a has returned part way, at least, toward normal position. The purpose of such construction is to render it impossible to operate the 60 game device twice from a single coin. It will be remembered that dog a^2 is held in engagement with shoulder e^3 by friction only. Consequently as soon as the handle is rotated backward the slightest amount the dog will 65 become disengaged from said shoulder and cannot be again thrown into engagement therewith until after another coin had been introduced into the slot. It is desirable, further, to so design the arm a^6 and parts of 70 the escapement that said arm will not engage arm i^2 to release the escapement until handle a has almost reached normal position on the return movement. The object of this arrangement is to prevent the operation of the parts 75 until the handle has practically returned to normal position. The operator may therefore be as deliberate in his movements as he desires, but is assured that the collecting and repositioning parts will not commence to 80 move until he is ready and desires them to do so, which desire he signifies by letting go of the handle, or at least permitting it to return almost to normal position. As a result of the above construction the operator may 85 procure as long an interval as he wishes between the scattering of the balls and their repositioning. Inasmuch as sleeve a' , to which handle a is attached, is loose upon shaft e , there is nothing to prevent the handle 90 from being again rotated forward before the escapement completes its movement. This would permit the spring-influenced finger i to swing into the path of the rapidly-rotating fan h' and subject the parts to danger of breakage. To avoid this, I have 95 formed a yoke or U-shaped bend i^3 in shaft i' , adapted to be engaged by the hook or catch e^6 , as best shown in Figs. 3, 6, and 19. Said hook is pivoted upon the stationary hanger 100 b^{15} , secured to plate b' , and is spring-influenced, so that its forward hooked extremity tends to drop toward said yoke i^3 . A pin e^7 , fastened to and projecting laterally from wheel e^4 , is adapted to strike the lower edge 105 of said hook e^6 to raise the same against the influence of the spring, and the parts are so arranged that said hook e^6 will remain in engagement with yoke i^3 from the time when said finger i is first withdrawn from fan h' until a time just before the wheel e^4 has completed its return to normal position. At 110 about the end of the return rotation of wheel e^4 pin e^7 strikes the lower edge of hook e^6 and raises the same, so as to release the yoke i^3 . This would permit the arresting-finger i to 115 again swing into the path of fan h' but for the fact that when the handle a is in normal position the arm a^6 thereon will be engaging the arm i^2 on shaft f to hold said arresting-finger in retracted position.

Cue-operating mechanism.—Referring more particularly to Figs. 5, 9, and 13, the cue j is loosely mounted in the stationary sleeve b^7 , so as to freely reciprocate therein for propelling 120

ling the cue-ball d' . Said cue is urged in a forward direction by means of the springs $j' j'$, which are preferably coiled springs located on opposite sides of the cue, as best shown in Fig. 5. The outer ends of said springs are secured to the rear inner wall b^8 of the casing b . It has been found to be advantageous to thus provide a pair of oppositely-located springs, for the reason that they prevent the binding of the cue in sleeve b^7 and render the operation more smooth and certain. Said springs j' are auxiliary, as far as their propelling effect is concerned, to the flat spring j^2 , which in the present design is vertically arranged and secured at its lower extremity to the lower portion of the wall b^8 . The upper and free extremity of said spring, which is preferably a flat spring, is also secured to cue j at a point behind sleeve b^7 and wall b^8 . The cue is retracted against the force of its springs by means of the retractor k , which consists of a lever fulcrumed, preferably, between its extremities in plate b' . The upper extremity of said retractor is adapted to engage the dog j^3 , which is pivotally secured to the rear extremity of the cue and hangs pendent therefrom. The construction is such that when the upper extremity of the retractor moves rearward it will first retract said cue and then suddenly release the same, so that it will be shot forward under the influence of the springs above mentioned. When the upper extremity of the retractor subsequently moves forward, the dog will yield by swinging about its pivot, and thus permit the retractor to again assume a position in front of said dog. Said retractor is operated by means of a rod k' , which is pivotally connected to the lower extremity of the retractor k and is also connected to the crank-disk k^2 , loosely mounted upon shaft f , as best shown in Figs. 9 and 13. Said crank-disk is rotated through a comparatively small arc by means of the arm f^7 , rigidly secured to shaft f . Said arm f^7 is located at the side of the crank-disk k^2 in position to engage the pins k^3 and k^4 , projecting laterally from said crank-disk. When the parts are in normal position, they will remain as indicated in full lines, Fig. 9, and dotted lines, Fig. 13. The parts are so timed that arm f^7 when rotating in the forward or clockwise direction will engage pin k^3 near the end of the forward rotary motion; and will then rotate said crank-disk until the retractor has moved to its rearmost position. (Indicated in full lines, Fig. 13.) Afterward when shaft f and arm f^7 thereon begin to rotate in the return or anticlockwise direction the arm f^7 will at first back away from pin k^3 and have no effect on the loose disk; but finally near the end of the rotation of shaft f arm f^7 will engage pin k^4 and rotate the disk back to normal position. (Shown in dotted line, Fig. 13.) In other words, arm f^7 rotates the disk

forward by means of pin k^3 and back again by means of pin k^4 . The object in this construction is merely to obtain lost motion, so that the operation of the retractor may be confined to a time near the end of the forward motion of shaft f and near the end of the return motion thereof. The object in having the cue retracted prior to the completion of the forward movement of shaft f (and handle a) is to have the propelling-springs j' and j^2 strained by the handle itself instead of depending upon the force of the motor-spring g . The retraction of the cue requires ordinarily a considerable amount of force, and I prefer to have such force imparted directly by the operator.

Although I refer to the part j as a "cue" and it is here shown in a form analogous to the form of cue employed in the ordinary game of pool, it is obvious that the form and method of mounting may be greatly varied without departing from the spirit of the invention.

Arranged in the form of a rectangle at the edges of table c and at a point somewhat inside of the marginal walls of the casing b are the four inner walls b^8 , b^9 , b^{10} , and b^{11} , to which the cushions b^{12} are fastened in the ordinary manner. At the four corners and at the middle of the two sides are located pockets adapted to receive the balls from the table when the latter is in horizontal position. Leading from each of said pockets is an inclined runway which leads to the tally means, which will be hereinafter described. The table c above mentioned fits within said inner walls and is pivoted at one edge, so that it may be placed in horizontal or inclined position. In the preferred construction here shown said table is hinged to the rear inner wall b^8 .

Table-operating mechanism.—The free extremity of said table c is raised and lowered at the proper time by means of the rod m , which is vertically movable and guided by the stationary portion b^{14} , which also forms a runway or hopper for guiding the object-balls in a manner hereinafter described. Said rod m is raised and lowered by means of the lever m' , which is pivoted in the stationary hanger m^2 , as shown in Figs. 9 and 12. The table merely rests upon said rod; but in order to relieve the parts of unnecessary jar it is desirable to attach a weak spring m^3 to lever m' , so that the parts may drop of their own weight, but will do so slowly and smoothly. Said lever m' is positively operated by means of the cam f^8 , formed upon disk f^9 . Said disk is rigidly secured to shaft f , and the parts are so timed that when said parts are in normal position, said rod will hold said table horizontal, but after the cue has been shot will permit said table to be lowered to inclined position for causing the balls to roll from the table onto the runway n .

Said runway n is fastened to the wall b^{10} in position to receive the balls as they roll from table c . Below said runway and connecting therewith is a second runway or trough n' , which is also fastened to wall b^{10} at the top of runway b^{14} . A gate c' is fastened to the under side of table c in such manner as to retain the balls in trough n' when said table is lowered and release the balls when the table is raised; this action being illustrated in Fig. 9. The purpose in thus retaining the balls in trough n' is to hold them there until all have been collected from the various parts of the device and then release them all at once. This is for insuring the proper distribution of the balls, so that they may be repositioned for subsequent play.

The manner of operation of the above parts is best illustrated in Fig. 10, taken in connection with Figs. 5 and 9. It is to be understood that one of the balls is to be returned to the cue-ball platform o , while the remainder of the balls are to be returned to the object-ball platform p . From trough n' there is a runway n^2 , leading to the platform o , which runway is wide enough to receive only one ball. Also leading from trough n' is the wide runway or hopper b^{14} , which leads to the object-ball platform p . To assist in directing the object-balls to platform p , it is desirable to provide stationary guides n^3 and n^4 . Now while the gate c' is in lowered position the balls will collect in trough n' in the manner shown in Fig. 10, one ball being adjacent to the entrance to runway n^2 and the others adjacent to the entrance to runway b^{14} . As soon as gate c' is raised it will simultaneously release all of the balls from trough n' , with the result that one of them will enter runway n^2 , while all of the remainder will run to the platform p .

Lift means.—The platforms o and p are adapted to support the balls, and for retaining the balls in position upon the platforms downwardly-yielding retaining walls or cups o' and p' , respectively, are provided. In this the preferred construction (best shown in Figs. 9 and 11) the cups have formed thereon sleeves o^2 and p^2 , respectively adapted to slide upon rods r and s , respectively. Bosses or collars r' and s' are formed on said rods to act as supports for coiled springs for urging the respective cups upward. As a result of this downwardly-yielding feature of the cups they are enabled to retain the balls upon the respective platforms while the latter are in lowered position and yet sink out of the way when the platforms are flush with the table.

Table c has a cue-ball aperture c^2 and object-ball aperture c^3 , the former being large enough to receive but one ball and being located in front of the cue. The aperture c^3 is located near the opposite end of the table and is adapted to receive the object-balls. Although the number of object-balls is not es-

sential, the preferred number is six, as this number permits an arrangement of the balls into the form of a triangle, as in the regular game of pool. As it is desirable to have the object-balls close together when positioned on a level with the table ready for play, it is desirable that the aperture c^3 be tapered so as to contract upward, the top of the opening being just sufficient to permit the elevation of the balls through it. The platforms o and p are of such size that they will closely fit their respective apertures when their top surfaces are flush with the top of the table.

It has been mentioned that the platforms o and p are raised and lowered by means of the rods r and s . These rods are rigidly secured to the lifting-yoke t , which in turn is raised and lowered by means of the lever u , pivoted on the stationary post u' . (See Fig. 11.) One extremity of said lever u is slotted to receive the pin t' , fastened to the vertically-apertured boss t^2 of yoke t . By means of a link u^2 the lever u is connected to one extremity of lever u^3 , which is fulcrumed upon the stationary post u^4 . The opposite extremity of lever u^3 is pivoted to the connecting-rod u^5 , pivoted to the crank-disk u^6 . Said disk is loosely mounted upon shaft f and is raised from lowest to normal position by the arm f^{10} , rigidly fastened on shaft f . As best shown in Fig. 11, said arm is located at the far side of disk u^6 in such position as to engage the pin u^7 , projecting laterally from said disk. The arm f^{10} in the present design of the machine is in engagement with pin u^7 for only about an eighth of a revolution at the end of the return or anticlockwise movement of shaft f . The extreme positions between which arm f engages pin u^7 are both shown in dotted lines, Fig. 11. The purpose in operating under this lost motion is to cause the rising action of the yoke t to occur just before the end of the return motion of shaft f and comparatively rapidly, so that disk u^6 may perform its function after all of the other devices have completed theirs. As the throw of connecting-rod u^5 is comparatively small and the required movement of the platforms o and p is comparatively large, the levers u and u^3 are compounded, the actual movement in the machine here shown being about seven to one. The proportions are not essential, however, the main idea being to have a comparatively great movement of the ball-platforms effected during a small part of the total active period of the mechanism. The weight of the yoke t and connected parts tends to cause them to drop; but there are four devices which act to sustain them at one time or another. These are the disk u^6 , (see Fig. 11,) the lever v , (see Fig. 11,) the keeper z , (see Fig. 16,) and the keeper y^2 . (See Fig. 17.) The construction and operation of the lever v and keepers z and y^2 will be hereinafter described; but there is a time after the rod y 13c

has been released from keeper y^2 and while arm f^{10} is at a point remote from pin u^1 when said yoke and connected parts are not supported. In order to prevent their falling too rapidly at such time, a counterweight t^3 is provided, which is attached to a cord t^4 , said cord passing over the fixed pulley t^5 and the other end being fastened to the yoke t .

Platforms o and p have three positions, in which they are presumed to rest for an appreciable period of time—to wit, low position, (shown in full lines, Fig. 11, and dotted lines, Fig. 9,) in which position the ball-receptacles receive the balls from their respective runways; final position, with the platforms o and p flush with the top of the table, and normal position, intermediate of the low and final positions. In normal position (shown in full lines, Fig. 9) the object-balls and cue-ball are partially within their respective apertures c^3 and c^2 and are consequently prevented from being accidentally disarranged.

The arm f^{10} and crank-disk u^6 , above described, act to raise yoke t from lowest to normal position, and this action occurs at the end of the return rotation of shaft f . The raising of said yoke from normal to highest or final position, with the top surfaces flush with the top of the table, is accomplished in the present design by means of the lifting-lever v , above mentioned, which is pivoted to the stationary bracket b^{16} , secured to the platform b' , as best shown in Figs. 9 and 11. The free extremity of said lever is adapted to engage the pin t^6 on yoke t to raise said yoke and parts thereon to final position. Said lifting-lever is operated by means of the cam e^8 , which is rigidly secured to shaft e and contacts lower edge of lever v for raising the same. The parts are so timed that this final lift is imparted to the platforms o and p just prior to the completion of the forward rotation of shaft e . The final lift, therefore, is accomplished directly by the operator in rotating handle a , which is preferable to requiring this work of the motor-spring g . One reason for this arrangement is that it affords simple means for obtaining the final lift just before the shooting of the cue and during the period of retraction of the cue. Another reason is that it relieves the motor-spring of the duty, which would otherwise be incumbent on it, of elevating the ball-platforms against the force of the yielding cups or receptacles o' p' .

Agitating mechanism.—As above mentioned, this game device is adapted to employ a plurality of object-balls, and it is necessary before said balls are played that they be positioned closely together. To assist in the proper gathering together of the balls, the object-ball receptacle p p' is of a configuration but slightly larger than the area which the balls when assembled will cover. The retaining-wall p' is so shaped that when the

object-balls are all in they make contact with each other and assume the form of a triangle. When the balls first run into the receptacle from runway b^{14} , one or more of them is apt to pile upon top of the others, their weight being insufficient to be depended upon to overcome friction and cause all of the balls to come down fairly onto the platform p . It is desirable, therefore, to provide special means for insuring the proper arrangement and settling of the object-balls within their receptacle before they reach the table. This adjusting and settling is accomplished by means of a special agitating or shaking device, which is shown separately in Fig. 14 and partially in Fig. 11. Rod s , upon which the platform p is secured, is mounted upon yoke t in such manner as to be rotatable about a vertical axis. The tappet-arm s^2 is rigidly secured to and extends horizontally from said rod s , and the tension-spring s^3 is connected to said arm and to the yoke t in such manner that said arm constantly tends to move toward the tappet-lever w . The function of said lever w with respect to arm s^2 is to move against it and swing it in an anticlockwise direction and subsequently produce a jarring thereof by first releasing and then suddenly arresting it. Said lever w is fulcrumed on the stationary bracket b^{17} , supported from plate b' , and is operated to swing back and forth by the rod w' , which is slidably mounted in the stationary bearing w^2 . Said rod is forced in one direction (to the right, Fig. 14) by means of the finger w^3 , which is mounted on rod w' in position to be engaged by the pins f^{11} f^{11} , secured to the farther side of the disk f^9 , hereinbefore mentioned. Said dog is pivoted to rod w' and has a tension-spring w^5 extending from it to said rod in such manner that when disk f^9 rotates in a clockwise direction, said dog will yield for the passing of pins f^{11} , but when said disk rotates in an anticlockwise direction the pins will move the rod to the right against the force of the spring w^4 . One extremity of said spring w^4 is fastened to the lever w , and the other extremity is fastened to the stationary hanger x , which will hereinafter be more fully described. The parts are so arranged and timed that as the rod s is rising from low to normal position the pins f^{11} , rotating in an anticlockwise direction, will successively strike the finger w^3 , thereby imparting an agitating vibratory motion to the lever w and a corresponding rotary motion to the rod s , for the rod w' will be moved to the right, Fig. 14, with a comparatively slow movement until one of the pins f^{11} releases said finger w^3 , at which time said finger will suddenly escape to the next successive pin f^{11} , against which it will suddenly be arrested. This will shake the object-ball receptacle in such manner as to insure the object-balls settling down properly therein.

Sustaining devices for the ball-receptacles.—Yoke t is rigidly fastened to and guided in its vertical travel in the machine by the rod y , which has a sliding bearing in the hanger x , 5 rigidly secured to plate b' . In the present design said rod also performs a second important function, which is to sustain the platforms o and p in normal position and in final position at a time when neither the arm f^{10} nor lever v is doing so. Referring more particularly to Figs. 7, 9, 15, 16, and 17, said rod has a notch y' , adapted to receive the keeper y^2 , which is slidably mounted on plate b' and is urged by the spring y^3 in a direction to 10 enter said notch. The lower approach to said notch is beveled, while the upper edge thereof is substantially horizontal, so that when the keeper is within the notch rod y will be sustained upon said keeper. The 15 upward movement of rod y will, however, force said keeper backward against the force of its spring. Said notch is so located on said rod that when resting upon said keeper said rod and the platforms o and p will be sustained in normal position. In order to force 20 keeper y^2 backward at the proper time to permit the lowering of rod y and the connected parts, a cam f^{12} is formed upon disk f^9 , as best shown in Fig. 15. A yielding finger y^4 is pivotally attached to the under 25 side of keeper y^2 at a point in line with cam f^{12} , and said finger is spring-influenced to tend to remain in contact with keeper y^2 . The parts are so arranged that when cam f^2 30 occupies the dotted position shown in Fig. 15 said finger y^4 will yield to permit said cam to rotate forward to the position shown in full lines without affecting said keeper; but the return rotation of said cam will force finger y^4 and keeper y^2 backward sufficiently to 35 release rod y and permit it to drop. The reason for thus providing special means for sustaining rod y and the ball-platforms in normal position is to enable the parts to remain 40 there when handle a is in normal position, at which time the arm f^{10} will be remote from pin u^7 . (See Fig. 11.)

Separate means are also provided for sustaining rod y in final position, with the ball-platforms o and p flush with the top of the table. These means consist of a keeper z , which is provided with a foot z' , adapted to enter beneath the lower extremity of rod y . The proportions are such that when rod y 55 rests upon foot z' said rod and the parts thereon will be in final position, with the ball-platforms level with the table. Said keeper z is urged by a spring z^2 toward rod y , as shown in Fig. 16, and is forced out of engagement 60 with said rod by means of the cam f^{13} , rigidly attached to shaft f . The two keepers y^2 and z are so timed with relation to arm f^{10} that the parts will operate as follows: Starting 65 with the parts in normal position with keeper y^2 sustaining rod y , let it be supposed that

the handle a is rotated forward from normal position. Near the end of the forward rotation of the handle cam e^8 will engage lever v and impart a final lift to yoke t and the ball-receptacles. This will raise rod y sufficiently 70 to permit foot z' to enter beneath it and sustain it for a short period—say, for example, about two or three seconds—while the balls are coming to rest after play. As the escape- 75 ment-spring now rotates shaft f in the return or anticlockwise direction it causes cam f^{13} to swing keeper z to dotted position, Fig. 16, to release rod y , at which time cam f^{12} (see Fig. 15) is in contact with finger y^4 to also hold keeper y^2 in retracted position. This 80 permits rod y to drop under the action of gravity to low position. (See full lines, Fig. 11.) The downward movement is made smooth and comparatively slow, however, by the counterbalance-weight t^3 , which is 85 somewhat lighter than rod y and the parts attached thereto. After the balls have been guided to their respective receptacles and the return movement of the motor-shaft is almost completed arm f^{10} comes into engagement 90 with pin u^7 and rotates disk u^6 one-eighth of a turn to normal position. This rotation of said disk sets the compound levers u and u^3 in motion and raises rod y , yoke t , and the ball-receptacles to the normal or 95 rest position, (indicated in full lines, Fig. 9.)

Tally means.—The tally means are designed to show into what pockets the balls have entered as a result of the play and to deliver one or more checks or tokens, the 100 number and value depending upon the number of balls pocketed and the values previously assigned to the pockets. Said tally means are illustrated in detail in Figs. 20 to 27, both inclusive, and are also indicated in 105 Figs. 5, 6, and 7.

In the present device there are six pockets into which balls may drop as a result of the play—to wit, the end pockets 1, the side pockets 2, and the end pockets 3, these last being 110 nearest to the cue. The stationary receiving-platform 4 has therein three apertures 5, 6, and 7, as best shown in Figs. 5, 7, and 20. From the end pockets 1 an inclined runway 8 leads to the aperture 5 in platform 4. The 115 inclined runways 9 lead from side pockets 2 to the aperture 6 in said platform, and the inclined runways 10 lead from the end pockets 3 to the aperture 7 in said platform. Said apertures 5, 6, and 7 are sufficient in size to 120 permit the balls to drop through them.

Beneath the stationary platform 4 is a tally-box 11, which is adapted to receive the balls dropping through platform 4 and has three compartments 12, 13, and 14, each of 125 a width and height slightly greater than the diameter of one of the balls, so that said balls may freely move therein. Said box has a top 15, having three apertures 16, 17, and 18 adapted to register with the apertures 5, 6, 130

and 7, respectively, and the compartments 12, 13, and 14, respectively. Said top 15 is so arranged that when it is in forward or normal position, as shown in full lines, Fig. 20, the balls will rest thereon or upon door 21, but when in rearward position will permit the balls to drop through into the box at a point behind the plungers 22. The box is adapted to slide upon the stationary guide-rod 19 and is moved back and forth thereon by means of the lug 20. (Best shown in Figs. 20 and 26.) Said lug is rigidly secured to said box and serves also to hold the box true and upright upon its guide-rod. Said rod is slightly inclined, so that the balls will tend to run out of the back end of the box into the runway 57, which leads to the collecting runway or hopper b^{14} . At the rear end of box 11 is hinged a door 21, which when closed serves to retain the balls within the tally-box to act upon the plungers 22. Said door is held in closed position by means of a dog 24, which is pivotally mounted on the box and spring-influenced to approach and engage said door. Said dog is caused to release the door at the proper time by means of the stationary cam or switch 25, which is fastened upon the stationary framework 26 26. After said door is released the box continuing to move forward brings the door against the rear end of rod 27, which thereby raises the door and holds it in raised position to permit the escape of the balls. This positive raising of the door is desirable, but might be accomplished by the weight of the balls themselves. In order to cushion the action, rod 27 is made yielding by slidably mounting it in the apertured lugs 29 31 on the tally-box. A collar 28 is formed on said rod and a weak compression-spring 30 interposed between it and the lug 29. The spring also acts to absorb backlash in movement of the box, for the parts are so arranged that after the door has been raised the forward one of the lugs 31 will contact the collar 28 and further compress the spring. Near the end of the return or backward movement after the door is free from rod 27 it will strike the stationary pin 32 in framework 26 and be positively closed, the dog 24 immediately snapping into engagement to keep it closed.

The plunger-rods 23, which carry the plungers 22 above mentioned, are mounted so that they will slide both relatively to the framework 26 and to the box 11. There is a plunger and plunger-rod for each of the compartments 12, 13, and 14, and in the initial position the plungers are back to the right, as illustrated in Figs. 20, 24, and 25. The parts are so proportioned that if the box moves forward empty to the end of its throw it will have no effect upon said plungers and rods, but with a single ball in a compartment the respective rod will be moved forward a distance equal to the diameter of one ball, or if there are two

or three balls in such compartment the plunger will be moved a corresponding amount. This is true of compartments 13 and 14; but in order that one check or token may be delivered every time the device is played and the box makes a complete stroke forward and back compartment 12 has a fillet 33, which is adapted to engage the corner of its plunger, but permits the passage of a ball. In the present design the plunger in compartment 12 is square, with corners for engaging the fillets and arresting the plunger; but other means for arresting said plunger at the proper point may be substituted. The forward edge of the fillet is at a distance from the rear edge of the box equal to the diameter of the ball, so that if there is one ball within compartment 12 it will have no effect additional to that of the fillet itself; but if there are two or three balls within the compartment the rod will be moved two or three diameters. Thus the operator is assured of getting at least one token every time he plays the machine, and he will get as many altogether as there are balls pocketed. This particular feature is designed for circumstances in which the machines are coin-controlled and placed in places of amusement and the tokens are redeemable by the proprietor in cigars or other merchandise. The player in such case receives some value for every coin deposited in the machine. It is not essential to the operation of the device that a check or token be always delivered; but the fillet affords means whereby this may be accomplished regardless to whether a ball has entered such compartment or not. It is obvious that the plungers in compartments 13 and 14 may be of the same shape as the one in compartment 12 or may be of any other shape such that a ball cannot escape past them. I also desire to point out the fact that the number of compartments is immaterial, and a box having one or any other number of compartments and plungers may be employed.

Upon each plunger-rod 23 is fastened a block 34 by means of a set-screw or otherwise, said blocks being adapted to engage the upper extremities of the levers 35 35. Said levers are fulcrumed upon the stationary bar 36 and are connected at their lower extremities to the lower extremities of the delivering-sectors 37 37 by means of the links 38. Said sectors are fulcrumed upon the stationary bar 39 in position to swing in a vertical plane beneath the chutes 40. There is one chute for each of the compartments in the tally-box and a delivering-sector at the bottom of each chute. The chutes are adapted to store a pile of checks or tokens 41, as best shown in Fig. 20, said tokens being preferably disks of metal, although other shapes and materials may be substituted. The upper edges of the sectors are circular and concentric with ful-

crum-bar 39 and so located that they will support the tokens in the chutes, the tokens resting upon the upper edges of the disks. One or more fingers 42 are mounted upon each sector with the upper edges projecting above the edge of the disk a distance not greater than the thickness of a single token. If a plurality of fingers are employed, as is the case in the preferred construction here shown, they will be at a distance apart somewhat greater than the diameter of a token, with the result that when the upper edge of the disks 37 move forward they will remove from the bottom of the pile as many tokens, one after the other, as there are fingers caused to sweep across the bottom of the chute. The parts are so proportioned that a single ball in one of the compartments in box 11 will produce sufficient motion to cause one of the fingers 42 to sweep across the bottom of a chute, while two balls will cause two fingers, three balls three fingers, and so on. This will thus effect the delivery of one, two, or three tokens, as the case may be.

In order that the fingers 42 shall not interfere with the tokens on the way back, they are pivoted to the segments, as shown in Figs. 20 and 27. A spring 43 is attached to the segment and to the fingers for normally retaining the latter in operative position, and the fingers are prevented by stop-pins 44 from yielding in the backward direction. The tokens delivered by the fingers from the storage-chutes drop into the receptacle 45, which is accessible from outside the casing.

The box 11 is moved back and forth by means of the arm 46, which is loosely journaled on the hub of the collar 47, pinned or otherwise rigidly secured to shaft *f*. In the preferred construction (best shown in Fig. 26) arm 46 has a transverse pin 48 fastened therein, and lug 20, above mentioned, is doubly slotted transversely, one slot receiving the arm itself to thereby maintain box 11 in upright position upon rod 19, and the second slot being adapted to receive said pin 48, whereby the box may be slid back and forth upon said rod 19. A second collar 49, also secured to the hub or collar 47, but on the opposite side of arm 46, forms a convenient means for keeping arm 46 in proper position at right angles to shaft *f*. These details of construction, however, are by no means essential, the principle being to provide a loose arm centered upon shaft *f* and capable when swung through a limited arc of imparting a reciprocatory movement to box 11. It is not essential that arm 46 constitute the means for holding box 11 level, for exterior guideways may be provided. As above indicated, arm 46 swings through a limited arc, although it has been previously explained that shaft *f* rotates approximately through one complete revolution. The rearward or clockwise swing of arm 46 is effected by

means of the pin 50, which is rigidly secured on the far side of collar 47 and projects in such manner as to engage the edge of said arm. This is indicated by the condition of the parts, Fig. 21. Arm 46 is swung in an anticlockwise direction to move the box forward by means of the dog 51, which has a shoulder 52, adapted to engage the pin 53, extending from the side of arm 46, as shown in Fig. 22. In order that the dog may release pin 53 at the proper time, it is pivotally mounted on collar 47, and a cam-surface 54 is formed on said dog, behind the shoulder, in such manner as to strike the rigid projection 55 and be depressed by the latter far enough to disengage pin 53. This feature is best illustrated in Fig. 23. The depressing of dog 51 by projection 55 permits the dog to continue its anticlockwise rotation without further affecting arm 46. A spring 56 is attached to collar 47 and to the dog for urging the latter toward pin 53 to engage it the next time the dog rotates in an anticlockwise direction.

Operation.—When the mechanism is at rest, the parts will occupy the positions shown in full lines, Figs. 9 and 20, except that all of the fingers of the delivering-sectors will be behind the token-chutes. To operate the device, all that the operator has to do is to drop a coin into the chute *b*, press the handle *a* down as far as it will go, and then release it and permit it to return to normal position. (Shown in Fig. 1.) During the forward movement of the handle the balls are raised to a level with the table, the cue is retracted and shot, the tally-box is pulled back into position to receive the balls that have been at this time pocketed by the cue, and the motor-shaft *f* is rotated forward one revolution, which stretches the coiled spring *g*, and thus provides power for further operating the mechanism. On the return movement of the handle nothing occurs until it has nearly reached normal position, at which time it causes the release of the escapement and allows the motor-shaft to commence its return rotation. The table then drops, allowing the balls that were not pocketed to run off the table into trough *n'*, where they are retained by means of the gate *c'*. At the proper time the tally-box is moved forward again to normal position, thereby pressing the balls therein upon the pistons 22 and causing the sectors 37 to deliver a number of tokens equal to the number of balls pocketed. Before the tally-box has quite completed its forward movement the door 21 at the rear thereof is caused to fly open and release the balls, which then run by gravity toward the assembling hopper or runway *b*¹⁴. In the meantime the ball-receptacles *o* and *p* have dropped to lowest position, so that the balls from the tally-box run into the object-ball receptacle *p*. About this time the table

begins to rise, thereby releasing the balls in trough n' , which all run to the receptacle p except one, which runs to the receptacle o . When the balls have reached their respective 5 receptacles, said receptacles begin to rise, at about which time the object-ball receptacle is agitated with a jarring rotatory movement to cause the balls to settle down into the proper triangular form. As the receptacles 10 start to rise the cam f^4 throws the auxiliary fan h^3 out of gear, thereby permitting increased speed in the motor-shaft, with a consequent gain in time in raising the ball-receptacles. The rising of the receptacles continues until the parts are brought back to 15 normal position ready for a repetition of the play.

What I claim as new, and desire to secure by Letters Patent, is—

- 20 1. In a game device the combination of a drop-table, a cue, a receptacle for a cue-ball in front of said cue, a receptacle for object-balls, means for shooting said cue, means for lowering said table to inclined position, means for lowering said ball-receptacles, 25 means for collecting the balls from the table when inclined and directing one of said balls to said cue-ball receptacle and the remainder to said object-ball receptacle, means for 30 raising said table to substantially horizontal position and means for raising said ball-receptacles to the level of said table.
- 2. A game device comprising a table, a ball, means for propelling said ball upon the 35 table to thereby put it in play, means for repositioning said ball upon the table, and devices for correlating said propelling means and repositioning means, whereby the ball is automatically repositioned after being propelled.
- 40 3. A game device comprising a table, a plurality of balls, means for propelling one of said balls toward the others, means for repositioning said balls upon different parts of the table, and means for correlating said propelling and repositioning means, whereby the balls are automatically repositioned after 45 propulsion.
- 4. A game device comprising a table adapted to lie horizontal when the device is in play, a ball free to roll upon said table, means for propelling said ball, means for subsequently repositioning the same, and means for correlating said propelling and repositioning means whereby the sequence of operation thereof is 50 regulated mechanically.
- 5. In a game device, the combination of a table, an object-ball, a cue-ball; means for propelling said cue-ball toward said object-ball and means for collecting and repositioning said balls.
- 6. In a game device, the combination of a table, an object-ball free to roll thereon, means for automatically positioning said ball upon said table, a cue-ball, means for prop- 65

elling said cue-ball toward said object-ball, and means for correlating said propelling and positioning means.

7. A game device comprising a table adapted to lie horizontal when the device is in play, 70 a plurality of balls free to roll upon said table, means for propelling one of said balls to act upon the others, means for repositioning the first propelled ball at one part of the table, other means for repositioning the other 75 balls at another part of the table and means for correlating said propelling means and both repositioning means for rendering the game device automatic.

8. In a game device, the combination of a 80 table, a ball, a spring, ball-propelling means urged by said spring, a handle, and a retractor operated by said handle for retracting said propelling means against the force of its spring, said retractor being adapted to release said propelling means when in retracted position, and subsequently reengage it.

9. In a game device, the combination of a 85 table, a ball, a spring, a cue urged by said spring and adapted to propel said ball, a handle, a retractor operated by said handle for retracting said cue, against the force of its spring, said retractor being adapted to suddenly release said cue when retracted, and means operated by said handle for repositioning said ball upon the table after being 95 propelled by said cue.

10. In a game device, the combination of a ball, a drop-table, means for holding said table normally in substantially horizontal 100 position, means adapted to move said table into inclined position, a runway adapted to receive said ball from said table when the latter is in inclined position, and means for subsequently positioning said ball upon 105 said table.

11. In a game device, the combination of a ball, a drop-table, means for holding said table normally in substantially horizontal position, means adapted to move said table into 110 inclined position, a runway adapted to receive said ball from said table when the latter is in inclined position, means for closing said runway against the admission of the ball when the table is in normal position, and a positioning receptacle for receiving the ball proceeding from said runway.

12. In a game device, the combination of a ball, a drop-table, means for holding said table normally in substantially horizontal position, means adapted to move said table into 115 inclined position, a runway adapted to receive the ball from said table when the latter is in inclined position, a gate for retaining the ball when the table is down and positioning 120 means adapted to receive the ball proceeding from said runway.

13. In a game device, the combination of a ball, a drop-table, means for holding said table normally in substantially horizontal posi- 130

tion, means adapted to move said table into inclined position, a runway adapted to receive the ball proceeding from said table to direct it to a predetermined point, and lift means located at said point and adapted to raise the ball, substantially as described.

14. In a game device, the combination of a ball, a drop-table, means for holding said table normally in substantially horizontal position, means adapted to permit said table to drop into inclined position, a runway adapted to receive the ball from said runway and to direct it to a predetermined point, means adapted to automatically raise said lift means, and other means adapted to lower said lift means when the latter is in raised position.

15. In a game device, the combination of a ball, a table pivoted upon a horizontal axis, and adapted to assume horizontal and inclined positions, means for rotating said table about its pivot, a runway adapted to receive said ball from the table when the latter is in inclined position, and means for subsequently positioning said ball upon the table.

16. In combination, a table, a ball, means for positioning said ball upon the table, means for propelling said ball, a handle for operating said propelling means and said positioning means, and devices for controlling the times of operation of said propelling and positioning means.

17. In combination, a table, a plurality of balls, means for rolling said balls upon said table, means for repositioning said balls, tally-tokens, tally means for delivering the same, a handle for putting into operation said ball-rolling means and said repositioning means and said tally means, and devices for controlling the times of operation of said ball-rolling means, repositioning means and tally means.

18. In a game device, the combination of a ball a drop-table, lift means adapted to raise said table into normal and substantially horizontal position, means adapted to sustain said table in raised position, a ball-receptacle adapted to lift the ball to the level of the table when the latter is in raised position and means for sustaining said ball-receptacle in raised position.

19. In a game device, the combination of a ball a table, means for positioning the ball upon said table, means for propelling it upon said table, and spring-driven means for operating both of said means, substantially as described.

20. In a game device, the combination of a ball, a table, means for propelling the ball upon the table, a spring for urging said propelling means, means for repositioning said ball upon said table after said ball has been propelled, a second spring for urging said positioning means to operate the same, a handle for straining both of said springs, and means whereby the said handle is adapted to release the spring of the propelling means first and

the spring of the positioning means afterward.

21. In a game device, the combination of a table, a ball, means for positioning said ball upon said table, means for propelling said ball upon said table, means for returning said ball from said table to said positioning means, a handle, means operated by the handle for driving said positioning and ball-propelling and ball-returning means, and correlating devices for controlling the times of operation of said positioning and ball-returning and ball-propelling means.

22. In a game device, the combination of a table, an object-ball, means for positioning said ball upon said table, means for propelling said ball upon said table, and means for returning said ball from said table to said positioning means, springs for operating said ball-positioning means, ball-propelling means, and ball-returning means, a handle for straining said springs and correlating devices for controlling the times of operation of said ball-positioning means, ball-propelling means and ball-returning means.

23. In a game device, the combination of a ball a drop-table, means for supporting said table and adapted to hold it normally in substantially horizontal position, said supporting means being also adapted to drop said table into inclined position, a runway adapted to receive the ball from said table when inclined and to direct said ball to a predetermined point, and means adapted to raise and lower said table-supporting means.

24. In a game device, the combination of a ball, a table adapted to swing about a horizontal axis, means for operating the table to bring it alternately to horizontal and inclined positions, a vertically-movable receptacle for carrying said ball, means for raising said receptacle to the height of the table when in level position and lowering said receptacle to a position below the table when the latter is in inclined position so that the balls may roll from the table to the receptacle, and devices for correlating said table-operating means and said receptacle-operating means.

25. In a game device the combination of cue and object balls a drop-table, having an aperture therein for the cue-ball, and an aperture for an object-ball; means for raising and lowering said table vertically-movable receptacles for carrying said balls, means for moving said receptacles to a top position flush with the raised position of the table, and to a bottom position lower than the lowered position of the table for the purpose described.

26. In a game device, the combination of a ball; a table; means for propelling the ball upon the table; means for positioning said ball upon said table; two springs, the first for urging said propelling means and the second for urging said positioning means; a handle

for straining said springs; an escapement for controlling the operation of said positioning means, and means whereby the said handle is adapted to release first the propelling means and afterward the escapement and through the escapement the spring of the positioning means.

27. In a game device the combination of a plurality of object-balls, a cue-ball, means for propelling said cue-ball toward the object-balls, a table having an aperture therein, a platform for elevating said object-balls to the level of the table through the aperture therein, means for propelling said propelling means means for elevating said platform, and devices for correlating said propelling means and platform-elevating means whereby the parts are so timed as to elevate said platform to the level of the table automatically just prior to the operation of said propelling means.

28. In a game device the combination of a cue, a cue-ball, a table having an aperture therein, a platform for elevating said cue-ball up to the level of said table through the aperture therein, said cue-ball loosely fitting said aperture, means for both shooting said cue and elevating said platform, correlating devices for timing said shooting and elevating means to automatically elevate said platform to the level of the table just prior to the shooting of the cue, and ball-confining means located below the level of the table for governing the lateral position of the cue-ball the normal position of the platform being below the level of the table whereby the cue-ball is retained within its confining means prior to the shooting of the cue.

29. In a game device the combination of a cue, a cue-ball, object-balls, a table having an aperture therein, a platform for elevating said object-balls up to the level of the table through the aperture therein, means for shooting said cue, means for elevating said platform, and correlating devices for timing said elevating mechanism and cue whereby the elevating mechanism automatically raises the platform to the level of the table just prior to the shooting motion of the cue, said platform normally resting below the level of the table for preventing premature scattering of the object-balls.

30. In a game device the combination of a ball, a table having an aperture therein through which the ball may be elevated to the level of the table, a platform for elevating said ball, and a downwardly-yielding wall adapted to retain said ball in said platform prior to the entrance of the ball into the aperture in the table.

31. In a game device the combination of a cue-ball, means for propelling the same, a drop-table hinged at one end for permitting said ball to roll off when said table is in inclined position, means for raising and lower-

ing said table and correlating devices connecting said propelling means and said table-operating means whereby said table is held in raised position during the propelling action of said propelling means and said table is subsequently lowered and again raised prior to the next succeeding propelling action of said propelling means.

32. In combination, a table, a ball, means for positioning said ball upon the table, means for propelling said ball, a handle for operating said propelling means and said positioning means, and devices including a fan-escapement for controlling the times of operation of said propelling and positioning means.

33. In a game device, the combination of a table, a ball, means for propelling said ball upon said table, means for positioning said ball upon said table, and correlating devices operative upon said propelling means and positioning means for automatically controlling the times of operation thereof, said correlating devices including a fan-escapement for modifying the rate of operation of said positioning means.

34. In an automatic game device the combination, with the game-playing parts of a spring for driving the same, hand-operated means for straining said spring, a fan-wheel escapement for governing the speed of operation of the parts under the influence of said spring; said escapement comprising two independent fan-wheels, one of which is a permanent part of the escapement and the other of which is auxiliary, a clutch for throwing the auxiliary fan-wheel into and out of engagement with the first, and a cam device for operating said clutch, said cam device being adapted to throw said auxiliary fan-wheel out of engagement with the first some time prior to the return of the driving-spring to normal condition, the retarding influence of the escapement being therefore greater at the time when the force of the spring is greatest.

35. In a game device having stationary parts and movable playing parts the combination, including such parts, of a master member for operating said movable parts; a spring operative upon said master member to return it to normal position; a hand-lever adapted to move said master member forward from normal position against the force of said spring, said hand-lever being adapted to return to its normal position independently of said master member; an escapement for governing the return movement of the master member under the influence of said spring; a spring-influenced escapement-arrester, urged to project said arrester to stop the motion of the escapement; a dog for holding said arrester in retracted position means operated by said hand-lever for throwing said dog and arrester into engagement with

each other and means operated by said master member for disengaging said dog from said arrester.

36. In a game device the combination, 5 with the stationary parts of a table hinged at one end, means for raising and lowering the free end of said table to bring it to inclined position and to substantially horizontal position, balls adapted to be played on said table, vertically-movable lift means for elevating said balls to the table when the latter is in horizontal position, collecting means for receiving said balls from the table when the latter is in inclined position and delivering them to said lift means when the latter is in lowered position, and correlating devices for timing said table and lift means whereby the lift means is lowered before the table is brought to inclined position and said lift 15 means is raised after said table is brought to horizontal position.

37. In a game device the combination, with the stationary parts of a table hinged at one end, means for raising and lowering the free end of said table, to bring it to inclined position and to substantially horizontal position, balls adapted to be played on said table, a vertically-movable platform for elevating said balls to the table when the latter 25 is in horizontal position, collecting means for receiving said balls from the table when the latter is in inclined position and delivering them to said platform when the latter is in lowered position, and correlating devices for timing said table and platform whereby said platform is lowered before the table is brought to inclined position and said platform is raised after said table is brought to horizontal position.

38. In a game device the combination, 40 with the stationary parts of a table hinged at one end, means for raising and lowering the free end of said table to bring it to inclined position and to substantially horizontal position, balls adapted to be played on said table, a vertically-movable platform for elevating said balls to the table when the latter is in horizontal position, inclined runways for receiving said balls from the table when 45 the latter is in inclined position and delivering them to said platform when the latter is in lowered position, and correlating devices for timing said table and platform whereby said platform is lowered before the table is brought to inclined position and said platform is raised after said table is brought to horizontal position.

39. In a game device, the combination of a ball, a table adapted to swing about a horizontal axis, means for operating said table for alternately swinging it to horizontal and inclined positions, a ball, receptacle for raising said ball to the table, means for conveying the ball to said receptacle from the table, 60 means for operating said ball-receptacle, and

correlating devices for timing the operation of said table, operating means and said receptacle-operating means, said correlating devices including a fan-escapement, a spring for driving it and a handle for both straining the spring and controlling the escapement. 70

40. In a game device, the combination of a ball, a table adapted to swing about a horizontal axis, means for operating said table for alternately swinging it to horizontal and inclined positions, a ball-receptacle for raising said ball to the table, means for conveying the ball to said receptacle from the table, a driving member having a limited movement, a compound lever connecting said driving member and said ball-receptacle whereby said receptacle receives a greater movement than has said driving member, said table-operating means being also connected to and operated by said driving member. 80

41. In a game device, the combination of a ball an apertured table, a platform for raising said ball to the level thereof and the downwardly - yielding retaining - wall upon said platform. 90

42. In a game device, tally means consisting of a token-receptacle, a member adapted to move in proximity thereto, and a set of fingers on said moving member each adapted to remove a token from said receptacle, said fingers being arranged in series, whereby the number of tokens removed depends upon the amount of motion of the member wherein said fingers are mounted. 95

43. In a game device, tally means consisting of a token-receptacle, having an opening therein through which a token may pass and a member having a set of projections arranged in series and adapted to move across the opening in said receptacle for removing tokens therefrom one after the other, substantially as described. 100

44. In a game device, tally means consisting of a token-receptacle having an opening therein through which a token may pass, a member adapted to reciprocate in proximity thereto and a set of fingers on said reciprocating member for removing tokens from said receptacle, said fingers being yielding in one direction for permitting return movement of the reciprocating member. 115

45. In a game device, tally means consisting of a token-receptacle, open at the bottom a sector pivotally mounted beneath said receptacle for supporting the tokens therein, 120 and projections on said sector for removing tokens from said receptacle.

46. A game device including balls, tally means consisting of a token-receptacle, movable members for removing tokens therefrom, 125 plungers for operating said movable members, a reciprocating tally-box adapted to receive one and also more than one ball behind said plungers for operating said plungers and moving them different amounts depending 130

upon the number of balls in the tally-box behind them, a power device and means operated by said power device for first moving said tally-box forward and subsequently returning it to original position behind said plunger for operating them.

47. A game device including balls, tally means consisting of a token-receptacle, movable members for removing tokens therefrom 10 plunger for operating said movable members, a reciprocating tally-box adapted to receive the balls behind said plunger for operating them, a door, the back end of the box for retaining and releasing the balls, and means 15 for operating said door.

48. A game device including balls, tally means consisting of a token-receptacle, movable members for removing tokens therefrom plunger for operating said movable members, a reciprocating tally-box adapted to receive the balls behind said plunger for operating them and means for automatically 20 reciprocating said tally-box.

49. A game device including balls, tally means consisting of a token-receptacle, movable members for removing tokens therefrom plunger for operating said movable members, a reciprocating tally-box adapted to receive said balls behind said plunger for operating them, a door at the back end of the 25 box for retaining and releasing the balls; and means for automatically opening said door.

50. A game device including balls, tally

means consisting of a token-receptacle, movable members for removing tokens therefrom 35 plunger for operating said movable members, a reciprocating tally-box adapted to receive the balls behind said plunger for operating them, a door at the back end of the box for retaining and releasing the balls; and 40 means for automatically closing said door.

51. A game device including balls, tally means consisting of a token-receptacle, a delivering-sector, a plunger for operating said sector, a reciprocating tally-box adapted to 45 receive a ball behind said plunger and in front of the back wall of the box, whereby the said back wall may act upon the plunger through the ball, and means for reciprocating said box.

52. An automatic pool-game apparatus consisting of a casing, a table, a plurality of balls, means for propelling one of them against the others, means for repositioning them upon the table, tally - tokens, tally 55 means for delivering said tokens, and means for operating and means for timing said propelling means, repositioning means and tally means.

In witness whereof I have hereunto subscribed my name in the presence of two witnesses.

BERTRAM C. KENYON.
